UNITED STATES PATENT OFFICE

GEORGE J. ZIEGLER, OF LOS ANGELES, CALIFORNIA, ASSIGNOR OF ONE-HALF TO
CHARLES J. HEYLER, OF LOS ANGELES, CALIFORNIA

NOZZLE FOR PICKING COTTON

Application filed January 22, 1929. Serial No. 334,267.

This invention relates to an appliance for picking cotton and the like and the principal object thereof is to provide a suction nozzle that can be directed toward the ripe cotton or ripe unopened bolls with means connected with the nozzle for catching the product and drawing it into the nozzle so that suction will carry it on to a receiver. To that end I provide a nozzle having a suction operated turbine arranged adjacent its inlet end with means connected to the turbine for actuating a pair of rollers connected to a fixed and movable jaw on the nozzles that are driven to catch the cotton and draw it into the nozzle as stated.

15 Features of invention are shown in the construction, combination and arrangement of parts whereby a nozzle is provided that is especially adapted to pick cotton that tenaciously clings to the cotton bolls or to gather cotton that ordinary suction will not dislodge from the bolls and also to pick and crush the ripe unopened cotton bolls.

Other objects, advantages and features of invention may appear from the accompanying drawings, the subjoined detailed description and the appended claims.

The accompanying drawings illustrate the invention, in which:

Fig. 1 is a semidiagrammatic view of a nozzle constructed in accordance with this invention showing it in use.

Fig. 2 is an enlarged side elevation of the nozzle also showing a fragmental portion of the flexible suction pipe to which it is secured.

Fig. 3 is a plan view of the nozzle shown in Fig. 2.

Fig. 4 is a section on the line 4-4, Fig. 3, showing a detail of the turbine wheel and cage and also indicating by dotted lines the arrangement of the train of gears for driving the cotton picking rollers.

Fig. 5 is a section on line 5-5, Fig. 3, showing the arrangement of the nozzle jaws and also the picking rollers; also showing by dotted lines an altered or open position of the upper jaw.

Fig. 6 is an enlarged side view of the nozzle with the turbine wheel and cage removed showing the gear connection between the tur-

bine wheel and the lower roller; also showing the housing for the outer gear in section and the air ports in the side of the nozzle head.

Fig. 7 is a fragmental section on the line 7-7, Fig. 2, showing the arrangement of the turbine on the side of the nozzle head.

The nozzle 10 is connected to the inlet end of a flexible pipe 11 that has its discharge end connected to an inlet manifold 12 that is in communication with a suction producing apparatus 13 mounted on a truck 14, as semi-diagrammatically illustrated in Fig. 1, so that the nozzle can be carried in advance of the truck and around in a cotton field from bush to bush to gather the cotton, it being understood that there are a number of nozzles connected by flexible pipes to the manifold with a number of persons manipulating the nozzles and a driver operating the truck and suction apparatus so that a wide swath can be harvested as the truck is driven over the cotton field. The nozzles are all substantially alike so that only one is shown and described in detail.

The nozzle 10 includes a head 15 in which there is a chamber 16 and integral with this head is an under jaw 17 that preferably is inclined upward.

Pivottally connected to the head 15 by a hinge 18 is an upper jaw 19 that is normally pressed toward the lower jaw by a leaf spring 20 that is secured to the head 15.

A pair of coacting rollers 21, 22 have their ends reduced and journaled into the respective jaws 17, 19; and they are frictionally engaged and arranged to be rotated so as to gather cotton from the bushes and deliver it to the chamber 16 in the head, from where it is carried by suction through the pipe 11 to the apparatus 13. The roller 21 is driven by gears 23, 24 and 25 that are driven by a turbine wheel 26. The wheel 26 is arranged in an open cage 27 that is connected by screws 28 to a disk 29 that is secured by screws 30 to the side of the head 15.

The turbine is constructed so that when suction is established in the nozzle by the apparatus 13 the air will pass through the ports 31 in the cage 27 and through the vanes 32 to

to drive the turbine wheel 26 and thereby drive the roller 17 which in turn drives the roller 19 so that when the nozzle is extended to within reach of the cotton or the ripe cotton bolls the rollers pick the cotton and deliver it into the nozzle where the suction moved air passing from the turbine into the nozzle through the opening 33 in the side of the head 15 carries the cotton through the pipe 11 to the apparatus 13.

Guides 34 are arranged on each side of the movable jaw 19 so that when it is open air will not be drawn into the nozzle from the sides of the jaw. However, it is understood that there is considerable suction between the rollers when they are separated by cotton or the ripened bolls, and this suction aids the rollers in drawing the product into the nozzle. This suction, however, is not sufficient to effect the actuation of the turbine to drive the rollers.

The tension of the spring 21 and the drive of the turbine is sufficient to easily crush the fully ripened but unopened cotton bolls as they pass between the rollers 17, 18.

The wheel 26 is provided with a hub 35 mounted on a bearing pin 36 secured in the cage 27 and the inner end of the hub 35 is provided with a stem 37 to which the drive gear 23 is secured so that when the turbine wheel 26 is revolved it will drive the roller 17, and consequently also drive the roller 19.

The gear 25 is enclosed by a housing 38 so it can not contact with the loose cotton on the bushes when in use.

In operation the nozzle 10 is preferably carried in front of the truck 14 which, as stated, carries means for producing sufficient suction in the nozzle to actuate its turbine with sufficient speed to drive the picking rollers 17, 19 with considerable force. When the rollers are so driven the nozzle is manually manipulated to bring it into contact with the cotton and ripened unopened cotton bolls which it will dislodge from the cotton stalks and carry into the nozzle, and, as previously stated, the air that operates the turbine also carries the picked cotton from the nozzle through the pipe 11 to the apparatus 13.

The apparatus 13 is capable of developing sufficient suction to simultaneously operate all of the nozzles that are connected to the manifold 12 and all of the nozzles are constructed and operated substantially alike.

If desired the rollers 17, 19 can have spaced rubber teeth 40 secured in slots 41 as best indicated in Figs. 5 and 6.

I claim as my invention:

1. A cotton picker including a suction pipe with an inlet head having a rigid jaw, an opposing yielding pivoted jaw cooperating therewith to form the inlet, engaging rollers on said jaws at the inlet between which the cotton enters the inlet, and means for driving said rollers, whereby the yielding jaw will

vary the space between the rollers as the cotton being gathered demands.

2. A cotton picker including a suction pipe with a head having a fixed jaw and a mouth at the end and an air inlet opening in the side of the head near the mouth, an opposing jaw pivoted to said head for varying the size of the mouth, rollers mounted in said jaws substantially filling said mouth, a turbine with a cage secured to the side of the head over said air inlet, and gearing driven by said turbine for operating the rollers.

In witness whereof, I have hereunto affixed my signature.
